DESIGN FOR A CUP OR SIMILAR ARTICLE

Alfred Langford, Stoke-on-Trent, England, assignor to The Coalport China Company (John Rose & Co.) Limited, Stoke-on-Trent, England

Application November 13, 1939, Serial No. 88,204

Term of patent 14 years

To all whom it may concern:

Be it known that I, Alfred Langford, a British subject, residing at "Stokesay," Wilton Road, Hanford, Stoke-on-Trent, England, have invented a new, original, and ornamental Design for a Cup or Similar Article, of which the following is a specification, reference being had to the accompanying drawing, forming part thereof.

Fig. 1 is a perspective view of a cup or similar article, showing my design;

Fig. 2 is a side elevational view; and

Fig. 3 is a rear elevational view thereof.

I claim:

The ornamental design for a cup or similar article, as shown.

ALFRED LANGFORD.
